UNITED STATES PATENT OFFICE.

CLARENCE E. ROHRER, OF ELKHART, INDIANA, ASSIGNOR TO SCHEIDEL-WESTERN X-RAY COIL CO., OF CHICAGO, ILLINOIS, A CORPORATION OF ILLINOIS.

METHOD OF EXCITING X-RAY TUBES.

1,194,071.

Specification of Letters Patent.

Patented Aug. 8, 1916.

Application filed December 16, 1913. Serial No. 806,985.

To all whom it may concern:

Be it known that I, CLARENCE E. ROHRER, a citizen of the United States, residing at Elkhart, in the county of Elkhart and State 5 of Indiana, have invented certain new and useful Improvements in Methods of Exciting X-Ray Tubes, of which the following is a specification.

One of the objects of my invention is to 10 improve X-ray apparatus to the end that the operative efficiency is enhanced; the capacity of the tube increased and its durability, or useful life, is prolonged.

Another object of my invention is to 15 provide an apparatus for the economical utilization of high potential alternating electric current, by rectifying selected cycles thereof and appropriating and directing the uni-directional impulses arising from such cycles, or parts thereof, from the alternating circuit into a derived circuit containing the tube and discarding, without rectifying, intermediate cycles, whereby providing a series of strong, undulating uni-directional 20 impulses capable of effecting an intense cathode stream, by their forceful impacts against the target of the tube, producing maximum X-ray penetration and definition.

In using an X-ray tube it is necessary that 25 the current shall pass in one direction, only, through the tube so that the cathode stream will not be interfered with by the passage of electric current in the opposite direction, which would set up inverse current effects 30 in the tube and destroy its effectiveness.

It has, heretofore, been customary to select a small fraction of each wave, usually 35 the crest of the wave of a given polarity of each and every cycle of an alternating, high potential current and to entirely discard all 40 waves of the opposite polarity without rectifying any part of the alternating current. By this means a very small percentage of 45 the entire current is employed for useful purposes.

In systems of this character, in which only 50 the crest of the succeeding waves of a given polarity are taken for useful work in the tube, a single circuit only is necessary, the 55 tube being included in said circuit in direct series relation with the source of alternating current supply.

In my apparatus both waves, or fractions

thereof, of given, or selected cycles are utilized, and intermediate cycles are rejected. 55

In making the entire cycle available for X-ray purposes, it is necessary that the current impulses be rectified, or that the direction of current of one wave impulse be changed to coincide with the direction of the 60 other wave impulse of the cycle.

In carrying my invention into effect I provide a derived circuit in which I include the X-ray tube, and in which current impulses only of a given direction are allowed 65 to flow, from the alternating circuit. Between this derived, direct current circuit and the alternating current circuit, which latter contains the source of alternating current supply and in which alternating current cycles are produced, I employ a cycle selector 70 and current rectifier whereby cycles are selected and then rectified into current impulses of uni-directional character, which are conducted into the direct current circuit, 75 and by which intermediate cycles are rejected, and not rectified. Thus every alternating cycle may be appropriated or every alternate cycle may be selected for useful work and the respective intermediate cycles 80 discarded or one alternation or half cycle may be taken and three intermediate alternations rejected. This spacing of the uni-directional current impulses produces better X-ray effects than may be produced when 85 every cycle is rectified and appropriated, as the effect in the tube is all that can be desired and the elimination of certain of the periodic cycles from the tube contributes to prevent rapid accumulation of excessive heat 90 which is transferred to the glass and liable to cause it to crack and break asunder and thus destroy the tube.

Figure 1 is a diagrammatic representation of the apparatus by means of which my 95 invention may be carried out. Fig. 2 is a diagrammatic representation of alternating current waves with every other cycle eliminated, and; Fig. 3 is a similar view with groups of three alternations eliminated out 100 of every two cycles.

The cycle selector is preferably composed of two disks A and B of insulating material such as mica, adjustably mounted on a shaft C which is driven in synchronism with the 105 current alternations or preferably by a syn-

chronous alternating current motor D. Spaced around the disks A and B, are eight current collectors 1-1', 2-2', 3-3', and 4-4'. Collectors 1-1' are connected together by the wire 5. Collectors 2-2' are connected together by wire 6. Collectors 3-3' by wire 7. Collectors 4-4' by wire 8. The secondary coil S, of the transformer, is connected to wires 5 and 7 by wires 9 and 10 respectively. The collectors 2' and 4 are connected to cathode and anode terminals, respectively, of the tube, by wires 13 and 14. Each disk carries on substantially 90 degrees of its periphery, an electric connector segment 11 and 11', respectively. They are disposed on opposite sides of the diameter of the disks and extend over such portion of the circumference of the disks as may be necessary to rectify the amount of the current wave that it is necessary to employ.

When the disks are rotated in synchronism with the alternations of the current, as they must be, they will make one revolution to each two cycles or four alternations of the current, and each wave, of every cycle, is operated upon, and thus a series of unidirectional impulses, corresponding with the number of waves, of the selected cycles will be collected and available for the tube.

Assuming that the positive wave comes from the secondary coil S over the wire 9, it will pass to collector 1' over wire 5 to the connector 11' of disk B, thence to collector 2' and over wire 12,—in the direction of the arrow—to the cathode terminal of the tube. From the anode terminal of the tube, over wires 13 and 8 to collector 4; over connector 11 to collector 3, thence over wire 7 to wire 10 and to the secondary coil S. The next positive impulse will come from coil S over wire 10 to collector 3', by this time the disks have made one quarter revolution and the connectors 11-11' are in dotted line position. Current will then flow from collector 3' over connector 11'—dotted line—to collector 2', thence through the tube to collector 4, connector 11—dotted line—to collector 1 and over wires 5 and 9 to coil S. The next, or third positive wave or alternations will come in at 1 pass to 2, thence over wire 6 to the tube and back over wires 8 to 4' over 11' to 3' and thence to S. The fourth wave will come in at 3 over 11 to 2, over 6 to tube, thence over 8 to 4', over 11' to 1' and back to S, thus rectifying two cycles at each revolution.

Suppose that we eliminate collector 2' by opening switch 12', then collector 2' is "dead" and one complete cycle will be rejected or discarded and the current will be such as diagrammatically represented in Fig. 2 in which every alternate cycle is appropriated and rectified and intermediate cycles are discarded, as shown by the arrows. It is obvious that switch 12' may be

placed in the wire leading to any collector or other than 2' with the same result.

Now if another collector, either 1' or 3' be disconnected, from the wires by which they are included in circuit as by opening switches 20 or 21, then the direct current impulses, appearing in the direct current circuit, would be fairly represented by diagram Fig. 3 where one alternation is selected and rectified and three intermediate alternations are discarded. Under such circumstances current in the tube circuit could only pass from collector 4' over connector 11' to whichever collector 1' or 3', is left connected in circuit.

If desired other disks could be added and greater variations than those specifically disclosed herein could be produced.

The illustrated exemplification is thought to be sufficient for a clear disclosure of my invention without further elaboration, as I realize that changes may be made in the size, number and disposition of parts within the scope of the appended claims, without departing from the spirit of my invention.

Having described my invention, what I claim is:

1. The combination with a transformer, an X-ray tube, and a motor driven shaft, of a pair of disks of insulating material mounted in spaced relation on said shaft, a metallic segment on each disk in diametrically opposite position, a pair of diametrically opposite collector brushes for each disk, the brushes of one pair being in axial alignment with those of the other pair, circuits connecting adjacent brushes of each pair to one of the secondary terminals of the transformer and the opposite adjacent brushes to the other secondary terminal, a second pair of collector brushes for each disk positioned at approximately 90 degrees to the first pair, circuits connecting adjacent brushes of each second mentioned pair to one terminal of the X-ray tube and the opposite adjacent brushes of the second mentioned pairs to the other terminal of the X-ray tube and means for disconnecting one of said brushes from its associated terminal.

2. The combination with a transformer, an X-ray tube, and a motor driven shaft, of a pair of disks of insulating material mounted in spaced relation on said shaft, a metallic segment on each disk in diametrically opposite position, a pair of diametrically opposite collector brushes for each disk, the brushes of one pair being in axial alignment with those of the other pair, circuits connecting adjacent brushes of each pair to one of the secondary terminals of the transformer and the opposite adjacent brushes to the other secondary terminal, a second pair of collector brushes for each disk positioned at approximately 90 degrees

to the first pair, circuits connecting adjacent brushes of each second mentioned pairs to one terminal of the X-ray tube and the opposite adjacent brushes of the second mentioned pairs to the other terminal of the X-ray tube, means for disconnecting one of the brushes from a terminal of the X-ray tube, and means for disconnecting one of the

brushes from its connection with a secondary terminal of the transformer.

In testimony whereof I hereunto set my hand in the presence of two witnesses.

CLARENCE E. ROHRER.
